UNITED STATES PATENT OFFICE.

WALTER S. SHIPE, OF TORONTO, CANADA.

MACHINE FOR FORMING ROLLED LONGITUDINAL JOINTS IN CYLINDERS.

SPECIFICATION forming part of Letters Patent No. 508,350, dated November 7, 1893.

Application filed April 4, 1892. Serial No. 427,730. (No model.)

To all whom it may concern:

Be it known that I, WALTER SCOTT SHIPE, of the city of Toronto, in the county of York, in the Province of Ontario, Canada, have invented a certain new and Improved Machine for Forming Rolled Longitudinal Joints in Cylinders, of which the following is a specification.

The invention relates to improved means for making a longitudinal joint, patented by me in the United States on the 9th day of June, 1891, and in Canada, on the 15th day of September, 1891, which consists of a T-iron strip placed between the edges of the sheet to be joined, the portion of the strip projecting between the edges being compressed or riveted down substantially flush with the outer surface of the cylinder which was previously done by a hammer, and the object of the present invention is to provide a light and quickly operating machine by which the said longitudinal joint may be formed by swaging rollers, and it consists, essentially of a light mandrel provided with suitable clamping devices designed to rigidly hold the boiler with its jointing strip in position, the said mandrel being driven by mechanism by which it derives a quick reciprocating motion so as to bring the jointing strip below swaging rollers automatically operated so as to gradually compress the jointing strip substantially flush with the outer surface of the boiler, the whole being constructed in detail substantially as hereinafter more particularly explained.

Figure 1, is a perspective view of my improved rolling machine. Fig. 2, is an enlarged end view of the driving gear. Fig. 3, is an enlarged detail of the trip by which the brake is applied. Fig. 4, is a detail showing the means for connecting the two belt shifting rods. Fig. 5, is a detail of the belt shifter. Fig. 6, is a cross section of the machine through x, y , Fig. 9. Fig. 7, is a front view of the feeding mechanism. Fig. 8, is a back view of the machine. Fig. 9, is a sectional view of the swaging rollers immediately over the trunnion with the boiler in position. Fig. 10, is a detail in section showing means by which the joint strip is forced out of its recess after the boiler is finished. Fig. 11, is a cross section of the saddle on which the boiler rests.

In designing my machine for swaging down the rib by which the longitudinal joint is formed, I have kept in view the fact that it is necessary that the machine should be constructed light enough to be able to be worked at a high speed and at the same time be sufficiently strong to resist the intense strain that it will be called upon to stand during the swaging of the metal forming the joint.

In the machine, as illustrated, I have arranged that the swaging tools shall be connected to the stationary frame of the machine, while the mandrel on which the boiler is placed is operated by machinery arranged to impart to it a reciprocating motion designed to bring all parts of the joint in contact with and so as to be acted upon by the said swaging tools, belt shifting devices being provided by which one belt is removed entirely clear of the driving pulley before the reversing belt is moved toward the said driving pulley. It will of course be understood that a great many points in the construction of the machine might be retained while making the portion of the machine which carries the boiler stationary and the portion of the machine carrying the swaging tools reciprocating.

For the purpose of this specification, I propose to first describe the mechanism by which the longitudinal movement of the boiler carrier or mandrel is imparted; secondly, the means by which the momentum of the stroke is checked before reaching the end of the stroke when the machine stops for the boiler to be put on or removed; thirdly, the belt shifting mechanism; fourthly, the clamping mechanism by which the boiler is secured in position, and fifthly, the swaging tools and mechanism for operating the same.

A represents a T-headed beam, on the end of which a leg B, is formed. This leg B, is bolted to a leg C, formed on the beam D, on which latter beam a rack D' is formed. The beam D, is supported by the truck E, carried on a suitable rail, as indicated. The bolts which connect the legs B, and C, are carried through oblong holes in order that the beam A, may be adjusted vertically to compensate for wear in the working parts of the machine. The rack D', meshes with the pinion F, which is keyed to the same spindle as the

worm wheel G, (see Fig. 2). This worm wheel meshes with a worm H, formed on or connected to the driving shaft I. It follows, therefore, that the revolving of the driving shaft I, imparts a longitudinal movement to the beam A. As the speed at which the beam A, travels will be necessarily quick, it is requisite that means should be provided by which its motion shall be checked and stopped 10 when the beam A, is thrown to the full end of its stroke to receive the boiler, as herein-after explained.

On reference to Figs. 1, 2 and 3, the mechanism will be understood. The driving shaft I, with its worm H, is journaled in a casing I', and has a disk J rigidly secured to its end, as shown in Fig. 2. Another disk K is fitted on said shaft; but is arranged to loosely fit thereon and has a cam-shaped portion S on its end, which acts against a similarly cam-shaped end S' on the end of the casing I', the purpose of which will be hereinafter described. An arm L, projects from the disk K, and extends over the latch O. A set screw N, is screwed in the end of the bar L, and normally rests upon the latch O, which is pivoted on the bracket P, extending from the housing Q. A push plate R, is placed on the bar M, at a point which will reach the latch O, just before the boiler carrier has reached the end of its stroke. The push plate R, is shaped so that it strikes and pushes aside the latch O, clear of the set screw N, thus permitting the arm L, to fall, and owing to the cam S, formed on the back of the disk K, (see Fig. 2) the said disk is jammed against the disk J, so as to check the speed of the driving shaft I and stop it, at which period both belts will be off the driving pulley. When the driving shaft is reversed, the arm L, is raised a short distance by friction between the disks (due to the frictional surfaces shown at K') and permits the latch O, to be thrown back by its spring beneath the set-screw N. This set-screw is provided so that the fall of the arm L, may be easily regulated.

On reference to Figs. 1, 2, 4, and 5, the construction and operation of my improved belt shifter will be understood. The two rods T, and U, are independently supported at one end by the bracket V, which extends from the main frame of the machine and has suitable bearings in it which support the rods T, and U, and permit them to move longitudinally 55 in the said bearings. The opposite end of each rod T, and U, is connected to an independent slide W, and X, carried in a suitable bracket Y, supported on the frame of the machine, as indicated in Fig. 1. On the bottom 60 of the bracket Y, I pivot the belt-shifters Z, and Z', each belt shifter having a crank formed on its pivot end from which a pin Y', projects through a slot in the bottom of the bracket Y, into the slot W', made in its re- 65 spective slide.

In Fig. 5, the belt shifters are shown in the position they will appear when the shifter Z,

is on the belt which at the time is driving and the shifter Z', on the loose pulley belt. It will, of course, be understood that these 70 belt shifters Z and Z' operate the belts z z, which belts drive the pulleys z' in a manner well understood. Assuming that both rods T, and U, are connected together, the pins Y', are located in their respective slots W', in 75 such a position that the simultaneous movement of the slides W, and X, will cause the belt shifter Z, controlling the driving belt for the time being to move first and after it the belt shifter Z', controlling the belt on the loose 80 pulley. Consequently the belt on the tight pulley is first removed before the belt running in the opposite direction is thrown upon the driving pulley.

In order that the belt shifting may be accomplished automatically, I place two adjustable stops T', on one of the rods T, or U, and between the two stops I place an arm S', which is fixed to and extends from the bar M, or other reciprocating portion of the machine, 90 and I connect the two rods T, and U, together by a link V', which is pivoted on one rod and designed to engage with the other, as shown in Fig. 4.

When the mandrel with its clamping devices is to be run out to the end of the stroke, as hereinafter explained, I disconnect the two rods T, and U, by raising the link V', clear of the one it is engaged with, and as the slides W, and X, are independent of each other and are independently connected to their respective belts, the rod which controls the belt at the time driving, may be readily adjusted at the proper time to arrest the motion of the machine as it approaches the end of the stroke 105 onto its loose pulley, thereby leaving the mandrel free to move by its own momentum, and it is at this time that the braking mechanism hereinbefore described comes into action.

On reference to Figs. 1 and 6 the manner 110 in which the boiler is clamped onto what I may fairly term its mandrel, and which I have before referred to in the specification as the T-headed beam A, will be understood. A saddle piece a, is placed on top of the beam 115 A, and is shaped as indicated in Fig. 6, to correspond in shape with the interior of the boiler b, which when inserted in position, as hereinafter described, rests upon it, as indicated in Fig. 6. On each side of the saddle 120 piece a, I place a clamping piece d, which corresponds in length with the saddle piece a, and is intended to act in conjunction with the said saddle piece, as hereinafter explained, to clamp the boiler against the said saddle piece. 125 e, represents a jacket made the same shape and length as the boiler. On reference to Fig. 6, it will be noticed that each edge of the jacket e, is fitted over the inner edge of the clamping pieces d, to which clamping 130 pieces the respective edges are riveted or otherwise securely fastened. A heavy head f, is bolted or otherwise powerfully secured to the housing g. On each side of the head f, I

carry in suitable adjustable boxes *h*, vertical rollers *i*, designed to act against the clamping pieces *d*, for the purpose hereinafter explained. In the drawings, I have shown bushing strips *d'* on the clamping pieces to receive the wear from the rollers *i*, but these strips may be used or not as the manufacturer sees fit. Each pair of rollers *i*, is operated by a spindle *j*, provided with right and left-hand screws so that the revolving of the spindle in one direction will cause the pair of rollers to approach each other, and when revolved in the other direction, to move apart.

On reference to Fig. 6, a pair of rollers *k*, will be seen. These rollers are situated in the center of the head *f*, and are designed to act against the top of the clamping pieces *m*, hereinafter referred to. The rollers *k*, are carried by eccentric spindles *n*, so that by turning the said spindles, the rollers *k*, may be raised or lowered as occasion may require. Each spindle is provided on its inner end with a shoulder *n'* and with a pin and set-screw *p*, on its outside by which the said spindles may be adjusted and held by friction at any position desired. Under each roller *k*, I place a strip of metal *q*.

The foregoing constitute all the parts by which the upper portion of the boiler is held in position and operated as hereinafter explained, and the following constitute the parts by which the lower portion of the boiler is held.

r, is a hollow beam which fits loosely the beam *A*, and is adjustably connected thereto by set screws or otherwise. This hollow beam is intended to fill the space between the bottom of the beam *A*, and the boiler *b*, lining pieces *s*, being placed inside the hollow beam as shown in Fig. 6. By providing the hollow beam *r*, with lining pieces *s*, I am enabled to readily and easily fill different sized boilers and thus form a solid mandrel on which the joint may be rolled, as hereinafter specified. Immediately below the head *f*, I place a trunnion carried by a block *u*. This block *u*, is detachable so that it may be easily removed and a higher or lower one substituted so as to suit the size of boiler to be acted upon. On top of the trunnion *t*, I place a heavy bar *v*, which fills up the space between the top of the trunnion *t*, and the bottom of the jacket *e*, which is secured to the bar *v* and encircles the boiler *b*. The other end of the bar *v* is connected to and supported by the leg *B*, as shown in Fig. 1, oblong holes being made in the said leg, as indicated in Fig. 1, so that the bar *v*, may have a slight vertical movement for the purpose hereinafter explained.

In order to support the clamping pieces *d*, I provide at one end of the bar *v*, a pair of links *w* (only one of which is visible in the drawings) supported by a horizontal pin projecting through the bar *v*, at one end, the said links being detachably connected to the clamping pieces *d*, at their other ends. The

links *w*, are movable on their supporting pin *x*, so that when the clamping pieces *d*, are not acted upon by the rollers *i*, they may be moved apart, which movement is effected by the natural outward spring of the jacket *e*. In order to assist this outward spring, and help to support the weight of the clamping pieces *d*, I place at the other end of the jacket a pair of spring bars *y*, shown by dotted lines in Fig. 1, which are connected to the clamping pieces *d*, and are set to effect the purpose desired.

Having now described the parts by which the boiler is secured to its mandrel, I shall proceed to explain how the said parts are manipulated for securing the desired end. The first thing I do is to run the mandrel out of the machine—that is to say, to run it past the center of the head *f*, so that the strips *q*, shall be past the rollers *k*, thus leaving the clamping piece *m*, free to be raised sufficient to permit the insertion of the boiler. The clamping pieces *d*, will also be clear of the back rollers *i*, while the front rollers *i*, which are visible in Fig. 1, are adjusted apart by turning their spindles *j*. Thus the clamping pieces *d*, will spring apart and the jacket *e*, open so as to permit the insertion of the boiler, the bar *v*, having fallen down by the recess *v'*, coming opposite to the trunnion *t*. When the mandrel is run out to the full extent for the purpose of receiving the boiler, I prefer to provide a temporary support of some kind to carry the bar *V*, and clamping pieces connected to it. On reference to Figs. 1 and 2, the means by which the mandrel itself is supported will be understood. On each side of the pinion *F*, I place a plain roller 19, which projects between the beam *D*, and the bar *M*. Consequently when the mandrel is run out to its full extent, any tendency to tip over is arrested by the beam *D*, coming in contact with the bottom of the said rollers 19. In order to raise the top clamping pieces *m*, I connect them together at their outer ends and pivot on them a lever 20. This lever is fixed to a spindle which is journaled in the clamping piece *m*, and has a foot fixed to its opposite end (not seen in the drawings) similar to the foot 21, formed on the end of its lever 20. The feet 21 operated by the lever 20 act against the clamping pieces *d*, and thereby the top clamping piece is elevated. Before putting the boiler in position, I insert the T-shaped strip *w'*, into a groove *a'* made in the saddle piece *a*, (see Fig. 6) which abuts against the stationary stop *z*, and is held between it and the endwise movable stop *z'*, at the opposite end of the recess, the strip *w'*, being placed between the said stops, so that the strip *w'*, cannot expand lengthwise when being swaged, as hereinafter specified. The boiler to be jointed is then slipped into the jacket *e*, and adjusted so that its edges shall be brought against the rib of the T-shaped strip *w'*, after they are compressed by the forcing together of the clamping pieces *d*. I

may mention here that the rollers *k*, are adjusted to suit the thickness of the metal forming the boiler and when once set to suit the gage of the metal, the set screws *p*, are secured and the eccentric spindle *n*, locked until boilers of a different gage are to be manufactured. When the boiler *b*, is placed in position, the machine is put in operation, and the swaging tools, which I shall now proceed to describe, are put into action.

On reference to Figs. 1, 6, 7, 8 and 9, the construction and operation of my swaging tools will be understood. In the center of the head *f*, immediately over the strip *w'*, I place a double disk *2*, in which disk I journal the rollers *3*, which constitute the swaging tools. The spindle *4*, on which the disk *2*, is journaled, is eccentric in shape, so that when the spindle *4* is revolved, the said disk *2* is raised or lowered as required. In the drawings I have shown only three swaging rollers *3*, but of course more or less may be used as required. As indicated in Fig. 6, the first roller is shaped so as to force down the edges of the boiler into the recess made in the strip *w'*, and the other rollers or swaging tools are shaped to swage down the center rib of the strip *w'*. Of course this strip, or the manner in which it is employed for the purpose of making this joint does not form any portion of my present invention, which is merely for a machine to make the joint by rolling or swaging the strip.

On reference to Fig. 8 which shows the back of the head *f*, it will be observed that an arm *5*, is fastened to the spindle *4*, which arm, when the spindle *4* is revolved, comes in contact with the lever *6* which is fixed to the same spindle as the hook *7* (see Fig. 9) which hook is intended to engage with one of the pins *8*, in the disk *2*, as indicated in Fig. 9. When it is desired to adjust the disk *2* so as to bring one or other of the swaging tools *3* in position to act upon the joint, I revolve the spindle *4*, which brings the arm *5* against the lever *6* and as the latter is connected by its spindle to the hook *7*, the said hook is raised clear of the pin *8* with which it may at the time be engaged. Simultaneously with the raising of the hook *7*, the disk *2* is raised, owing to the eccentric-shape of the spindle *4*. The relative positions of the pins *8* are such that when the hook *7* is gripping one of the pins *8*, one of the rollers or swaging tools *3* will be held immediately below the center of the spindle *4* in position ready to act upon the joint of the boiler. The center line through the full throw of the eccentric should be horizontal when the swaging tool is in position ready to commence working.

We will assume that the machine is in operation and that the boiler is being carried backward and forward under the swaging tool, shown in Fig. 9, and as it is necessary in order to accomplish the purpose of the said swaging tool that it should be gradually fed down at each stroke of the machine, I pro-

vide mechanism by which the necessary feed may be automatically and effectually accomplished, and the construction of this automatic feed will be understood on reference to Figs. 1, 6, and 7.

9, represents a wheel which is fixed to the spindle *4*. This wheel *9*, has three sets of ratchet teeth cut on its periphery. Each set of ratchet teeth, being made at a different pitch so that the feed, which is operated as hereinafter explained, may be fine or coarse to suit the class and weight of iron to be swaged. It will also be observed that each set of ratchet teeth on the wheel *9*, is commenced coarse and gradually becomes finer, so that the feed shall be quicker at the commencement than at the end of the feed. The importance of making this feed so that it will automatically decrease as the swaging of the joint nears its completion will be appreciated when it is remembered that the rib in the strip *w'*, can be readily compressed at the commencement of the swaging, but that as the swaging proceeds, the iron becomes harder and the surface greater by the spreading of the rib, making the work greater at each succeeding stroke. In practice I have found that the gradual reduction of the pitch of the ratchet teeth is not in itself sufficiently slow, and I, therefore, as before explained, set the spindle *4*, so that the center line through the full throw of the eccentric is horizontal when the swaging tool commences to work. Consequently the downward feed of the swaging roller by the action of the revolving of the eccentric *4*, is greatest as the center line of the eccentric leaves the horizontal and gradually reduces as the center line of the eccentric assumes the perpendicular.

On reference to Fig. 7, it will be observed that the pawl *10*, which engages with the ratchet teeth, as indicated is pivoted on an arm *11*, pivoted on the head *f*, and actuated by a spring *12*, which supports the pawl end of the arm *11*, as shown. In order to prevent the spring *12*, throwing the arm *11*, higher than desired, I provide an adjustable plate *13*, which butts against the bar *14*, as shown in Fig. 7. By the adjustment of the plate *13*, the projection *15*, on the arm *11*, may be permitted to enter the notch in the bar *14*, more or less as desired to suit the ratchet section then in use and prevent more than one tooth being taken at a time. It will of course be understood that the feeding down of the swaging tools must take place when the boiler is clear of the swaging tool. It is, therefore, necessary to arrange the stops by which the belt-shifting apparatus is regulated so that the boiler shall be carried about two or three inches past the swaging tool at each end of the machine. At this point, the stops by which the feed is operated are brought into action so that the spindle *4*, shall be revolved the required distance immediately that the boiler has passed the swaging tool at that time in operation. As the stop is a rapid one,

the ratchet wheel would revolve more than the required distance to move a single tooth. I therefore provide on the end of the arm 5 (see Figs. 6 and 8) a set-screw 18, having on its end a piece of leather or other suitable material to produce friction, and it is by the tightening of this set-screw against the head 7, that the spindle 4, is prevented being revolved by any sudden jar or quick motion of the pawl operating the ratchet wheel.

I may add to what I have already said, that the reason I commence the feed at the coarsest teeth of the ratchet and the travel of the eccentric of the spindle at its quickest moving point is, in order that the feed shall be slower and slower as the joint nears completion.

As shown in Fig. 1, the bar 14, is connected to a rod 16, which is suitably carried on the frame of the machine and is provided with two stops 17, one on each side of the arm S', which moves with the reciprocating portion of the machine, as before described. At each stroke of the machine, the bar 14 is moved so as to make its notch pass over the projection 15 and thus force the arm 11 down sufficiently far to move by the pawl 10 the ratchet wheel 9 a single tooth, and in this way the spindle 4, is revolved so as to move the swaging tool 30 down ready for the next stroke.

On reference to Figs. 10 and 11 the means by which the strip w', is removed will be understood.

Fig. 11, is a side-view of the endwise movable stop z', which stop, with the stop z, at the opposite end of the groove prevents the strip w' expanding lengthwise during the process of swaging. In order to remove the strip w' it becomes necessary to first slide the stop z' transversely of the mandrel by any suitable means so as to bring the slot 22 in it opposite to the end of the strip w', shown by dotted lines in Fig. 11. The strip w', must then be knocked out of its recess a', which is 45 accomplished in the following manner:

On reference to Fig. 10, it will be observed that there are three pins 23 projecting through holes made in the saddle piece a, immediately below the recess a' and below these pins in a 50 recess made in the beam A, I fit a bar 24 having its surface cam-shaped below each pin 23, so that the longitudinal adjustment of the bar 24, shall force the pins up vertically so as to push the strip w', out of its recess 55 and clear the stop z', the cam on the bar 24 which acts on the pin 23 nearest to the stop z' being shaped so that after forcing up the pin so as to completely clear the strip w' of the stop z', and allow the stop z', to be moved, 60 it permits the said pin to drop back again so as to permit the strip w', to drop loosely back while the boiler is being pulled off the mandrel.

I have shown and prefer to have the parts 65 carrying the boiler movable and the swaging parts stationary when in operation, but as before stated these conditions may be reversed,

and when in my claims I mention a reciprocating mandrel, or means for reciprocating the same combined with a stationary swaging device, I mean to include thereby reciprocating swaging devices and a stationary mandrel, as I consider such an arrangement of these parts as being a mere reversal, not requiring inventive ingenuity, and within 75 the spirit of my invention.

What I claim as my invention is—

1. A reciprocating mandrel provided with clamping mechanism arranged to rigidly hold the edges of a longitudinal joint of a boiler 80 against a T-shaped strip placed between its edges, in combination with a swaging roller suitably supported and provided with mechanism by which said swaging roller is gradually fed against the T-shaped jointing strip, 85 substantially as and for the purpose specified.

2. In a machine for rolling the longitudinal joint of a boiler and in combination with a swaging device, means for holding the boiler in position, a truck, a beam supported on said truck and adjustably connected to said boiler-holding means, a rack formed on said beam, a pinion engaging with said rack, and means for operating said pinion, thereby operating said boiler holding means and beam, substantially as and for the purpose specified. 95

3. In a machine for rolling the longitudinal joint of a boiler and in combination with a swaging device, means for holding a boiler in position, a truck, a beam supported on said truck and adjustably connected to said boiler-holding means, a rack formed on said beam, a pinion engaging with said rack, means for operating said pinion, a bar having a connection with said boiler-holding means and a 100 roller fitted on the spindle of said pinion and arranged to fit between said bar and beam, substantially as and for the purpose specified.

4. In a machine for rolling the longitudinal joint of a boiler, a mandrel provided with 110 means for holding a boiler in position and having a T-shaped base and arranged to substantially correspond with the interior of a boiler which it is designed to support, a U-shaped beam placed under said T-shaped 115 mandrel, and a lining piece between said mandrel and beam, substantially as and for the purpose specified.

5. In a machine for rolling the longitudinal joint of a boiler, and in combination with 120 a mandrel suitably supported and shaped to correspond with a boiler which it is designed to support, a jacket arranged to partly encompass the boiler, clamping pieces attached to said jacket and means, substantially as 125 described, for forcing said clamping pieces together to compress the boiler, substantially as and for the purpose specified.

6. In a machine for rolling the longitudinal joint of a boiler, a mandrel, comprising a 130 T-shaped beam having a saddle-piece placed on its head, and shaped to substantially correspond with the interior of a boiler which it is designed to support, in combination with

- a jacket arranged to partly encompass said boiler, clamping pieces attached to said jacket, means, substantially as described, for forcing said clamping pieces together, a second set of clamping pieces arranged substantially over said saddle piece, and means, as the rollers k arranged to depress the last named clamping pieces, substantially as and for the purpose specified.
- 10 7. In a machine for rolling the longitudinal joint of a boiler, and in combination with a reciprocating mandrel, spindles n eccentrically journaled in a suitable casing, rollers k carried by said spindles, clamping pieces m acted on by said rollers, a collar fixed to each spindle behind the roller, a set-screw bearing on the casing and a pin connected with the spindle and arranged to receive said set-screw, substantially as and for the purpose specified.
- 15 8. In a machine for rolling the longitudinal joint of a boiler, a mandrel, comprising a T-shaped beam having a saddle-piece placed upon its head, and shaped to substantially correspond with the interior of the boiler, a beam fitted on the base of said T-shaped beam, clamping pieces d , and a jacket connected to said clamping pieces, in combination with a bar v connected to said jacket, a
- 20 30 pin x projecting from said bar v and links w loosely fitted on said pins and supporting said clamping pieces, substantially as and for the purpose specified.
- 25 9. In a machine for rolling the longitudinal joint of a boiler, and in combination with a swaging device and a reciprocating mandrel thereof, a jacket, means for holding the same on a boiler, a bar v connected to said jacket, a recess made therein, and a roller arranged to support said bar v , substantially as described.
- 30 40 10. A mandrel suitably supported and having a saddle-piece a , a groove made in said saddle-piece to receive a T-shaped strip, and a stop z placed at one end of said groove and against which said strip butts, in combination with an endwise movable stop z' located at the end of the groove opposite the stop z , substantially as and for the purpose specified.
- 45 50 11. A reciprocating mandrel provided with clamping mechanism arranged to rigidly hold the edges of a longitudinal joint of a boiler against a T-shaped strip placed between the said edges, a roller arranged to form a stationary solid support for the mandrel, and a swaging roller located immediately over the supporting roller and provided with mechan-
- ism for feeding it down upon the strip at each stroke of the mandrel, substantially as and for the purpose specified.
- 60 12. In a machine for rolling the longitudinal joint of a boiler and in combination with a reciprocating mandrel, a disk 2 having pins 8 thereon and rollers 3 journaled thereto, an eccentric spindle 4 on which said disk is journaled, a hook 7 arranged to engage with said pins, a lever 6 fixed to the spindle of said hook, and an arm 5 fixed to the eccentric spindle and arranged to act on the said lever 6, substantially as and for the purpose specified.
- 65 13. In a machine for rolling the joint of a boiler, means for supporting and reciprocating said boiler, a spindle journaled in a suitable casing and having an eccentric portion, a disk 2 journaled on said eccentric portion, a swaging roller supported by said disk, a ratchet wheel 9 fixed to said spindle, and a pawl acting on said ratchet wheel, in combination with mechanism for operating said pawl, thereby operating the ratchet wheel, substantially as described.
- 70 14. In a machine for rolling the joint of a boiler, means for supporting and reciprocating the boiler, a spindle 4 journaled in a suitable casing and having an eccentric portion, a disk 2 journaled on said eccentric portion, a swaging roller supported by said disk, a ratchet wheel 9 fixed to said spindle and provided with teeth of different size, and a pawl 85 acting on said ratchet wheel, in combination with mechanism for operating said pawl, thereby operating said ratchet wheel, substantially as described.
- 75 15. The combination with a reciprocating mandrel and the swaging roller of a machine for rolling boiler joints, of a spindle 4 carrying said roller and eccentrically journaled in a suitable casing, an arm fixed to said spindle, and a brake arranged between said arm 100 and said casing, substantially as and for the purpose specified.
- 80 16. In a machine for rolling the longitudinal joint of a boiler, a mandrel, a longitudinal slot therein to receive a strip w' , and pins 23 inserted in said mandrel, in combination with a cam-faced bar 24 arranged to act against said pins, substantially as and for the purpose specified.
